Charles L. Wagner
BY George Young
ATTORNEY

UNITED STATES PATENT OFFICE.

CHARLES W. WAGNER, OF MILWAUKEE, WISCONSIN.

BRUSH-HANDLE ATTACHMENT.

1,311,581.

Specification of Letters Patent. Patented July 29, 1919.

Application filed July 15, 1918. Serial No. 245,032.

To all whom it may concern:

Be it known that I, CHARLES W. WAGNER, a citizen of the United States, and resident of Milwaukee, in the county of Milwaukee and State of Wisconsin, have invented certain new and useful Improvements in Brush-Handle Attachments; and I do hereby declare that the following is a full, clear, and exact description thereof.

10 This invention relates to new and useful improvements in brush handle attachments and more particularly to that type adapted to be adjusted with relation to the brush.

15 The principal object of the invention resides in the provision of a device of this character which can be attached to any type of brush now in common use.

20 Another object of the invention is the provision of a brush handle having an attaching plate provided with intersecting guide slots to permit adjustment of the handle in four directions.

25 A further object of the invention is the provision of an attaching plate provided with means adjacent the ends of its guide slots to hold a nut, carried by the handle, against rotation.

30 With these and other objects in view which will be apparent as the description proceeds, my invention resides in the novel features of construction, combination and arrangement of parts as hereinafter described and defined by the appended claim, it being understood that changes in the precise embodiment might be made by those skilled in the art without departing from the spirit of the invention.

35 This invention in one practical form in which it may be embodied is illustrated in the accompanying drawing in which:

40 Figure 1 is an elevational view of a brush with the invention attached thereto and shown in section.

45 Fig. 2 is a plan view of the attaching plate.

Fig. 3 is a detail sectional view through a portion of the invention, and

Fig. 4 is a detail view of the nut locking means.

50 Referring now more particularly to the accompanying drawings 1 designates an at-

taching plate, secured to a brush B, and having its central portion 1' arched upward and provided with intersecting guide slots 2 running longitudinally and transversely of the attaching plate. A handle 3 provided with a threaded end has mounted thereon a ferrule 4 having a threaded end 5 adapted to project through the guide slots 2 and having its end crowned to form a head 60 55 6. Threaded upon the end 5 and disposed interiorly of the arched portion 1' is a nut 7 adapted to bind the ferrule and attaching plate together to hold the handle in its adjusted position. 65

Adjacent the ends of the slots 2 are rib projections 8 which conform to the sides of the nut 7 and engage the same to prevent it from being rotated.

From the foregoing description it will 70 be readily seen that by a turn of the handle 3 sufficient to loosen the nut 7 the handle can be adjusted to any one of the four ends of the slots 2 where the nut 7 will be engaged by a flange 8 and upon a turn in the 75 reversed direction the handle will be locked in its adjusted position. Furthermore in providing the attaching plate with a central arch portion the plate can be attached to a flat surface, at the same time leaving sufficient space between the arched portion and surface of the brush to permit the handle to be traversed within the slots, without necessitating cutting away of the brush head. Inasmuch as the arched portion acts as a 80 85 strengthening reinforcement the attaching plate can be formed or stamped from a very light material, thus making the device simple and economical in construction.

I claim:

90 A handle attachment for brush heads comprising a plate arched and slotted longitudinally and transversely to provide angularly disposed side and end portions in which are disposed the end portions of its 95 slots, a handle socket bolt selectively extending through one of the slots, a clamping nut threaded on the bolt at the inner portion of the plate, an enlargement at the inner end of the bolt forming a retainer 100 for the nut whereby said nut, plate and handle socket bolt are permanently con-

nected, and angular shoulders at the ends of the slots, said shoulders being open toward their respective slots for the reception of the nut whereby said nut is held against 5 rotation when moved to the end of the slot.

In testimony that I claim the foregoing I have hereunto set my hand at Milwaukee, in the county of Milwaukee and State of Wisconsin.

CHARLES W. WAGNER.
